Jack Shain, Newton, Mass.

Application September 9, 1954, Serial No. 32,221

Term of patent 3½ years

(Cl. D47—2)

Fig. 1

To all whom it may concern:

Be it known that I, Jack Shain, a citizen of the United States, residing in Newton, in the county of Suffolk and Commonwealth of Massachusetts, have invented a new, original, and ornamental Design for a Knitted Fabric, of which the following is a specification, reference being had to the accompanying drawings, forming a part hereof.

In the accompanying drawing, Figure 1 is a plan view of the knitted fabric showing my new design, the opposite side being substantially the same, and Figure 2 is an enlarged view of Figure 1.

I claim:

The ornamental design for a knitted fabric, substantially as shown and described.
